DESIGN FOR A SANDAL

Iredell M. Smith, Richmond Heights, Mo.

Application December 22, 1938, Serial No. 81,939

Term of patent 14 years

To all whom it may concern:

Be it known that I, Iredell M. Smith, a citizen of the United States, residing at the city of Richmond Heights, county of St. Louis, State of Missouri, have invented a new, original, and ornamental Design for a Sandal, of which the following is a specification, reference being had to the accompanying drawing, forming part thereof.

Fig. 1 is a perspective view of a sandal; and, Fig. 2 is a side elevation partly in perspective, showing my new design.

I claim:

The ornamental design for a sandal, as shown.

IREDELL M. SMITH.
